UNITED STATES PATENT OFFICE

JOSE LECUONA, OF STOCKTON, CALIFORNIA

WINDMILL

Application filed July 21, 1928. Serial No. 294,388.

This invention relates to water pumping apparatus and particularly to one operating by a wind-mill.

The main object of my invention is to provide a windmill of this general character, having a foldable vane and a brake mechanism for halting the operation of the wind-wheel, with a simple and positive means for folding the vane and applying the brake whenever it is desired to halt the operation of the windmill.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of the complete structure partly broken out.

Fig. 2 is a top plan view of the upper portion of the apparatus.

Fig. 3 is an enlarged sectional elevation of the driving and control mechanism, with the wind-mill vane extended.

Fig. 4 is a side elevation, showing the vane folded.

Fig. 5 is a cross section taken on the line 5—5 of Fig. 3.

Fig. 6 is a cross section taken on the line 6—6 of Fig. 4.

Referring now more particularly to the characters of reference on the drawings, the numeral 1 denotes a suitable vertical frame which is surmounted by tubular member 2 secured thereto. Turnable on the tube is a sleeve 3 on the upper end of which is mounted a casing 4, a thrust bearing 5 between the tube and sleeve permitting free rotation of the latter and consequently of the casing. Projecting upwardly through the tube concentric therewith is the pump shaft 6 carrying the bevel pinion 7 on its upper end, the weight of the shaft being taken by the pinion and by a thrust bearing 8 between the pinion and the top of the tube.

The pinion meshes with a bevel gear 9 fixed on a horizontal shaft 10, journaled in the casing, the outer end of the shaft having a wind wheel 11 of common form secured thereto.

By means of the above arrangement it will be seen that the casing and parts supported thereby are free to rotate with any shift in the direction of the wind without affecting the engaging of the gear and pinion as will be evident. Pivoted on the end of the casing opposite the wheel and normally projecting outwardly is a frame 12 which supports a vertical wind vane 13, normally held in a plane at right angles to the forward face of the wheel as usual by a tension spring 14.

This vane is pulled to a non-operative position, or so as to be parallel to the wheel by the following means. Slidable on the sleeve 3 is a collar 15 which is connected by links 16 with one end of a lever unit 17 pivoted intermediate its end on the frame 12 adjacent the upper end thereof. This lever has a normal upward slant toward its outer end and has a pull cord 18 attached to such end and extending downward to a point convenient to an operator standing on the ground. Slidable on the sleeve independently of the collar 15 but resting thereon is a collar 19. This collar on one side has a link 20 which projects upwardly and at an angle to connect with the lower end of a substantially vertical lever 21 which is pivoted intermediate its ends in connection with the casing 4. The upper end of this lever is flexibly connected to a link 22 which is similarly connected to the vane frame 12 some distance rearwardly of the pivot thereof and on the side opposite the spring. When the cord 18 is pulled the collar 15 is raised and pushes the collar 19 up; the parts connected thereto being so proportioned that with a full upward movement of the collar, the upper end of the lever 21 will be swung forwardly or toward the wheel 11 a distance sufficient to cause the vane frame 13 to be swung laterally so that the vane is parallel to the wheel.

The use of the separated collars 15 and 19 enables the lever which controls the movement of the former to be fixed on the frame, without

interfering with the rotation of the collar 19 which would take place with any rotation of the casing.

At the same time as the vane is being thus moved to a non-operative position, the wind wheel is positively held from further rotation as follows: Fixed in connection with the shaft 10 is a drum 23 about which a transversely split brake-band 24 is disposed, the band being anchored at one end to the casing 4 as shown at 25. The ends of the band are formed with radial ears 26 and a spring 27 between the ears normally holds the band clear of the drum. Turnable on the shaft 10 is an arm 28 one end of which carries a pin 29 to engage the ear on the free end of the band and the other is connected to the collar 19 by a substantially vertical rod unit 30. The arm member is disposed so that when said collar is in its lowermost position the pin will be clear of the band ear; but when the collar is raised said arm will be rotated to engage the ear and compress the spring sufficiently to cause the band to be frictionally contracted about the drum, thus of course holding the wind wheel from rotation. The rod unit may if desired be formed as a pair of telescoping members capable of a certain amount of loose play before moving together as shown. This would permit the collar to move up a certain distance before the band actuating arm functions, and allows of a shorter arc of movement of the arm than could otherwise be the case.

31 The pump shaft toward the ground projects through a casing 31 which is supported by the ground and extends to the bottom of the well 32.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A windmill including a supporting structure, a member turnably surmounted on the same, a horizontal shaft above and supported from said member, a wind-wheel on the shaft, a brake drum on the shaft, a band about the drum and anchored at one end, an ear projecting radially from the other end of the band, an arm rockably mounted on the shaft adjacent the drum, a pin projecting from the arm parallel to the shaft for detachable engagement with the ear, and means controlled from below the member for turning the arm to cause the pin to engage the ear and compress the band about the drum irrespec-

tive of the turning of said member relative to the supporting structure.

2. A windmill including a supporting structure, a member turnably surmounted on the same, a horizontal shaft above and supported from said member, a wind-wheel on the shaft, a brake drum on the shaft, a band about the drum and anchored at one end, an ear projecting radially from the other end of the band, an arm rockably mounted on the shaft adjacent the drum, a pin projecting from the arm parallel to the shaft for detachable engagement with the ear, a sleeve slidable on the member, connecting means between the sleeve and the end of the arm opposite the ear to cause the arm to turn and the pin to be depressed against the ear when the sleeve is raised, and means for raising the sleeve at will.

3. A windmill including a supporting structure, a member turnably surmounted on the same, a horizontal shaft above and supported from said member, a wind-wheel on the shaft, a brake drum on the shaft, a band about the drum and anchored at one end, an ear projecting radially from the other end of the band, an arm rockably mounted on the shaft adjacent the drum, a pin projecting from the arm parallel to the shaft for detachable engagement with the ear, a sleeve slidable on the member, means for raising the sleeve at will, and connecting means between the sleeve and arm arranged to turn the latter in a direction such that the pin will engage the ear only after a certain upward movement of the sleeve has taken place.

4. A windmill including a supporting structure, a member turnably surmounted on the same, a horizontal shaft above and supported from said member, a wind-wheel on the shaft, a brake associated with the shaft, lever means for applying the brake, a vane swivelly mounted in connection with said supporting member for folding movement about a vertical axis, lever means for folding the vane, a sleeve slidable on the supporting member, means for raising the sleeve at will, a direct connection between the sleeve and the brake lever means to cause the brake to be applied when the sleeve is raised, and a separate and direct connection between said sleeve and the vane lever means to cause the vane to be folded when the sleeve is raised.

In testimony whereof I affix my signature.

JOSE LECUONA.
